FRANK P. ATKINS, OF CINCINNATI, OHIO, ASSIGNOR TO ATKINS & PEARCE MANUFACTURING COMPANY, OF CINCINNATI, OHIO, A CORPORATION OF OHIO

BEAD CORD

Application filed March 22, 1928. Serial No. 263,725.

My invention relates to bead cords and to processes for manufacturing same.

In the art there has been, during recent years, a constantly increasing interest in 5 beads for feminine adornment. Beads of every conceivable shape and size are strung on cords which are usually composed of linen or silk. Beads are usually either jewels or semi-jewels, and being hard minerals, their 10 movement on the cord which supports them results in a gradual fraying of the cord. Frequently the cords break and if this occurs while the woman wearing them is on the street, it often becomes impossible to recover 15 them. As the beads are often matched and arranged in sequence according to their sizes, the loss of one or more beads frequently ruins the value of those which were not lost.

It is the object of my invention to provide 20 a novel process for manufacturing bead cord which will result in the provision of cord which will have both unusually great tensile strength and great resistance power against fraying by the hard surfaces of the beads. Specifically it is the object of my invention to provide a bead cord which will have a 25 fibrous central strand of desired tensile strength and braided about the central strand, fine metallic wire which possesses the 30 necessary strength to resist fraying.

The above and other objects to which reference will be made during the ensuing disclosure I accomplish by that certain combination of parts of which I have illustrated 35 a preferred embodiment.

Referring to the drawings:—

Figure 1 is a diagrammatic view illustrative of the braiding operation.

Figure 2 is a diagrammatic view illustrative of the nature of the braid, the size of the 40 thread and strand of wire being much enlarged.

Figure 3 is a perspective view of my preferred type of bead cord on a much enlarged 45 scale.

I have not attempted to show a complete braiding machine nor the method of drawing the central strand of fibrous thread through the former plate over tension rolls and onto the shipping spool as my invention does not

specifically relate to the braiding machine per se, but merely to a new use for such a machine which results in my novel product.

It will be understood that driven rolls draw the various fine metallic wires, together with the fibrous central strand, through a plate having a hole of substantially the desired diameter of the cord, from whence the cord passes onto the driven rolls, which may be faced with suitable material to prevent slipping. Several turns around the rolls are made with the cord, after which it is guided to a winding shaft which rolls the cord up on a removable spool upon which the cord is usually shipped.

I have diagrammatically indicated in Figure 1 an exemplary type of braiding in which eight spools of fine metallic wire such as are indicated at 1 move in the path of a figure 8 as at 2, and the spools indicated at 3 move 70 around a like path indicated at 4.

The fine metallic wire is mounted on these spools so that eight continuous strands are used in braiding the wire around the fibrous core or central strand 5. As has been noted the strands of wire surrounding the central fibrous strand are passed through the hole 6 as they are drawn from the spools during the spool movement, said spools passing one another and each spool 1 acting to lay its strand of wire across the strand being dispensed from each spool 3.

The result of moving the spools in the manner described and withdrawing the wire through the forming plate at the same time is to form a square braid in which the wires cross, one the other, at the points 7, 8, 9 and 10.

By referring to the strand of wires as indicated at *a*, *b*, *c*, *d*, *e*, *f*, *g*, *h*, it will be noted that the wire *a* passes under the wire *b*, and at the same time, the wire *c* passes over the wire *d*, and so on, as per the diagram in Figure 2. At the next braiding step each wire will take the place of the next wire in the series, and will pass over its companion wire and this plan of braiding will be continued all the way around the pattern.

During the braiding operation, the central strand 5 will be drawn straight up from the intermediate space 11 between the spools,

forming a center for the braid with the braid fitting snugly about it. After the braid is completed the cord is wound around rolls in which the cord is naturally bent without kinks or breakage occurring.

- 5 I have found that using a fibrous core of silk such as D silk and using pliable number forty copper wire for the wire braiding that a bead cord may be provided which will have
10 a tension strength of over twelve pounds. The outer braided surface of copper will form a surface which will allow the bead to slide around on the cord without friction and with little or no tendency to fray the cord.
15 While I have specifically mentioned silk and copper wire substitutes for these materials may also be used. I may use linen thread or other thread to provide the tensile strength and I may use silver wire, or wire
20 made from aluminum, gold, iron, or various alloys such as may be required for the several purposes for which the cord may be used.

Having thus described my invention, what I claim as new and desire to secure by Letters
25 Patent, is:—

A bead cord having a central strand of fibrous silk material having desired tensile strength with strands of pliable wire braided thereabout providing an outer surface for the
30 cord which will resist frictional wear.
